Attorney.

UNITED STATES PATENT OFFICE.

EARLE S. ECCLESTON, OF LOS ANGELES, CALIFORNIA.

CENTRIFUGAL SEPARATOR.

Application filed June 1, 1926. Serial No. 112,921.

In this specification, and the accompanying drawing, I shall describe and show a preferred form of my invention, and specifically mention certain of its more important objects.

5 I do not limit myself to the forms disclosed, since various changes and adaptations may be made therein without departing from the essence of my invention as hereinafter claimed; and objects and advantages, other 10 than those specifically mentioned, are included within its scope.

My invention relates to devices adapted for separating and concentrating composite materials of various kinds by the action of centrifugal force. Its principal objects are; first, to provide improved means for accomplishing such separation by a continuous process; second, to furnish operating adjustments adapting devices of this kind for treating materials of different natures under various operating conditions; third, to improve the operating efficiency of such machines by increasing the yield per unit of expended power and per unit of cubical capacity; and, fourth, to 25 achieve these results by means of a relatively simple and inexpensive construction.

My objects are attained in the manner illustrated in the accompanying drawings, in which—

30 Figure 1 is an elevation of my improved separator, shown partly in section and with certain parts broken away to disclose its interior construction, the sections being taken on the line 1—1 of Fig. 2;

35 Figure 2 is a horizontal section of the above structure, taken on the line 2—2 of Fig. 1;

Figure 3 is an enlarged fragmentary view 40 of the nozzle construction and placement employed in my separator, the view being in vertical section and taken on the line 3—3 of Fig. 2;

Figure 4 is a front elevation of a portion of one of the above mentioned nozzle supports with a nozzle mounted thereon; and

45 Figure 5 is a fragmentary elevation of a portion of the rotatable bowl of the separator, showing diagrammatically the cooperative action of the plural nozzles employed therewith.

50 Similar reference numerals refer to similar parts throughout the several views.

In an application for patent filed by me in the United States Patent Office on April 2nd, 1925. (Serial No. 20,217) I showed and described a centrifugal separator of somewhat similar construction to that shown and de-

scribed herein. The two constructions are patentably different however, and the claims of the present application do not conflict with those of the former one.

60

The embodiment of my present invention that I have selected for illustrative purposes comprises a housing 6 which preferably is made in the form of an upright truncated cone. At the top of this housing is a cover plate 7 carrying a central vertical journal bearing 8. The bottom plate 9 of the housing is provided with a similar bearing 10, and suspended from the bottom is a hanger 11 carrying a third journal bearing 12 and a ball 70 thrust-bearing 13.

65

Within the housing is a rotatable inverted bowl 14, closely conforming to the shape and interior dimensions of the housing. This bowl has a cover plate 15 at the top provided with a short central quill-shaft 16 projecting upwardly and rotatable in bearing 8. Beneath cover 15, and spaced therefrom, is a suspended deflecting plate 17. The bowl is fixed upon a vertical shaft 18 at the bottom, the shaft being rotatable in bearings 10 and 12. Rotation of the bowl may be accomplished in any convenient and suitable manner, as by a pulley 19. The weight of the rotatable parts and the material therein is supported by thrust bearing 13.

75

Within the housing is a rotatable inverted bowl 14, closely conforming to the shape and interior dimensions of the housing. This bowl has a cover plate 15 at the top provided with a short central quill-shaft 16 projecting upwardly and rotatable in bearing 8. Beneath cover 15, and spaced therefrom, is a suspended deflecting plate 17. The bowl is fixed upon a vertical shaft 18 at the bottom, the shaft being rotatable in bearings 10 and 12. Rotation of the bowl may be accomplished in any convenient and suitable manner, as by a pulley 19. The weight of the rotatable parts and the material therein is supported by thrust bearing 13.

80

The conical shell of bowl 14 is pierced by a multiplicity of narrow arcuate orifices 20, arranged in spaced circumferential rings. Just below the orifices, on the outside of the bowl, 90 there are circular flanges 21. Thin retaining bands 22 are supported by these flanges and extend upwardly therefrom, the upper edges of the bands extending above the respective arcuate orifices and terminating considerably short of the circular flanges 21 above them.

85

The interior surface of housing 6 is provided with a plurality of equally spaced upright partition flanges 23, of which the machine illustrated has four. These partitions 100 are connected by a multiplicity of inwardly and upwardly sloping circumferential webs 24, forming launders for the collection of material thrown off by the revolving bowl. The webs are so placed that their upper edges will 105 be intermediate the top and bottom edges of the respective bands 22, and they are helically positioned on the inner surface of the housing so as to have a slight downward slant in the direction of rotation of the bowl. The mate-

90

rial caught by these interior launders escapes to the outside of the housing through long and 110

relatively wide arcuate orifices 25 through which a tool may be inserted in case of necessity, as when there is a tendency for the material to become clogged.

5 On the outer surface of the housing are a plurality of upright nozzle supports 26. These are made integral with the shell of the housing, are box-like in section, and are placed on the shell adjacent to the angular position 10 of the interior partitions 23. Exterior launders 27 extend helically downward from the respective nozzle supports in the direction of rotation of the bowl, and terminate short of the succeeding nozzle supports to provide 15 space for inserting upright ducts 28 for carrying off the concentrates that flow downwardly to them.

To provide a sufficiently close fit for ducts 28, the lower ends of the exterior launders may 20 be milled parallel to the adjacent exterior walls of the succeeding nozzle supports, where indicated by 29 in Fig. 2. The ducts are provided with holes 30 opposite the respective launders, so that material in the latter may 25 flow directly into them.

The nozzle supports are pierced radially by a plurality of holes 31 at levels just above each of the retaining bands 22 on the bowl. Composite nozzles of special construction, are inserted in these holes as shown at 32 in Figs. 1 30 and 2.

Typical nozzle construction is shown in Figs. 3 and 4. The form illustrated comprises 35 positioning fittings 33 bolted to the nozzle supports. These fittings have interior chambers 34 communicating, by means of small pipes 35 and interposed valves 36, with headers 37 which contain water under pressure. Fittings 33 are provided with gland nuts 38 forming 40 packed stuffing boxes 39. Closed end tubes 40, of smaller exterior diameter than the interior diameter of chambers 34, extend through packing 39 and the shell of housing 6. Their inner ends are slightly spaced from the rotatable bowl, and their outer ends project beyond 45 gland nuts 38. These tubes have hexagonal extremities 41, whereby they may be rotated, and are longitudinally slid able as well as being rotatable. When correctly positioned, 50 they may be held in place by the friction of packings 39. The tubes are intermediately pierced by orifices 42 and thus communication is established between their interiors and chambers 34, irrespective of the angular or 55 longitudinal position of the tubes in fittings 33.

The respective ends of tubes 40 are eccentrically and oppositely drilled for the insertion of considerably smaller nozzle tubes 43. The 60 latter fit snugly in these end holes, are longitudinally and angularly movable therein, and may be maintained in their desired positions by their snug fits in the end holes. The outer extremities of the nozzle tubes have squared 65 portions 44 so that they may be conveniently

turned. Their inner extremities, after insertion in tubes 40 are bent angularly downward, as at 45, to form discharge nozzles adapted for washing concentrates out of the spaces between the revolving bowl and the retaining bands 22. Intermediate holes 46 establish communication between the bores of the nozzle tubes and the interior of tubes 40, irrespec- 70 tive of their related angular positions.

The nozzle construction just described permits of discharging water under the desired pressure from headers 37 through the nozzle tips 45. It also permits of angularly and longitudinally positioning the nozzles, and of slightly raising or lowering them by means of 75 their eccentric mounting in the rotatable tubes 40. Nozzles 45 terminate, as stated above, in the spaces between bowl 14 and bands 22 below the upper edges of the bands, and they generally are directed slantingly downward 80 against the direction of rotation of the bowl.

In the operation of my invention for concentrating ores the material ordinarily is pulverized and mixed with water to form a flowable pulp of the proper consistency. This 90 pulp is fed into the top of the rotating bowl through quill-shaft 16. It is prevented by deflecting plate 17 from dropping into the bowl and is thrown outwardly by centrifugal force, as shown by arrow 47, against the upper wall 95 of the bowl. Centrifugal force will cause the material to remain on the wall of the bowl, and it will gradually work downwardly under the influence of gravity and the downwardly increasing diameter of the bowl. 100 During this process the heavier particles of the mass will work outwardly through the lighter particles, and be thrown outwardly from orifices 20 into the spaces between the outer surface of the bowl and retaining bands 105 22. The rate of removal of the material in these spaces will determine the rate at which it passes through orifices 20 because, if not removed, the orifices will become choked and permit no more material to pass through 110 them.

The above process is repeated at each circumferential row of orifices working downwardly and, when the bottom row of orifices has been reached, if the device has been properly operated, the separation process has been 115 completed and only tailings remain. The latter pass freely outward through the bottom orifices 48, as shown by arrow 49, flow downwardly over the sloping surface of bottom plate 9, and are discharged through the tailings chute 50.

The jets from nozzles 45 operate to continuously remove the concentrates from the spaces between the bowl and the retaining bands 22. The rate at which this removal takes place is 120 adjusted by means of valves 36 whereby the force and volume of the jets is controlled. The jets, when properly positioned in the way described act in the manner illustrated in 125 130

Fig. 5. The accumulated concentrates 51 are washed upwardly by the streams from the nozzles as shown at 52. Part of this material is centrifugally thrown off from the upper edges of the retaining bands, as at 53; part is washed upwardly against the under surfaces of flanges 21 and is thrown off from the bottom edges of their retaining bands, as at 54; and a third part clings to the surface of the 10 bowl and tends to work downwardly again, as at 55. However, the cooperative action of the succeeding nozzle prevents the return of this material, in the manner indicated at 56. The use of cooperating plural nozzles in the 15 manner described may be made to increase the efficiency of operation of each nozzle, and to thus increase the total yield of the machine in a manner entirely out of proportion to the mere plurality of nozzles. The actual number 20 of nozzles that it is best to employ in a given case must be determined with relation to the diameter of the bowl, its rotative speed, and such other factors as jet velocity, specific gravity of the concentrates, fluid characteristics 25 of the concentrates, direction of the jets, etc.

The concentrates thrown off from the revolving bowl are caught by the inner launders of the housing and flow outwardly therefrom, through orifices 25, into the outer launders. At this point the concentrates become 30 visible and may be sampled for analysis. They flow downwardly in the outer launders and through holes 30 into such of the upright ducts 28 as is desired.

The use of plural ducts at 28 permits of 35 making operating adjustments of each nozzle independently, to secure the maximum yield therefrom. This may be done without interference with the regular operation of the machine. Thus, for example, corks may be inserted in all but one of the holes 30 in one of the ducts to prevent inflow, and thus determine the yield per unit of time from the nozzle 45 causing the flow into the open hole of this duct.

Another, and more important, use of plural ducts is to permit of grading and separating the concentrates that come from different 50 portions of the machine. The heavier particles in the ore mass are thrown off first, and appear in the upper banks of launders. The concentrates gradually become lighter and the character of their content is altered as the 55 ore mass passes downward in the bowl. By means of plural ducts and the use of corks in their intake holes, the yield of the machine may be graded in various ways as desired. For instance the yield from several of the upper 60 banks of launders may be made to pass wholly into one of the ducts, and the yield from the other banks below may be wholly diverted into another duct. The machine then will yield two grades of concentrates. Obviously it is perfectly feasible to employ three

or more ducts at 28 to classify the concentrates into as many grades as there are ducts.

The use of an inverted bowl in a centrifugal separator, as herein described, results in a number of great practical advantages over 70 separators that employ upright bowls. The more important of these will now be explained.

In the previous upright bowl types of separators the ore mass is introduced at the bottom and works upwardly against gravity by reason of the progressively increasing centrifugal force due to the flare of the bowl. The diameter at the top of the bowl necessarily must be much greater than it is at the bottom, and the difference between the centrifugal forces at these points is great for this reason. This great variation in centrifugal force is objectionable. It results in making the ore mass at the top of the bowl so dense 80 and compact that it is hard to secure proper stratification of the material; and it becomes very difficult to remove the concentrates by means of the jets.

In the inverted bowl of the present invention the ore mass is introduced at the top and gravity aids it to work downwardly over the inferior revolving surface. Consequently the bowl may have much less taper than upright bowls and may even be almost cylindrical in form. Great variation in the centrifugal forces is avoided in this way; the body of the ore mass becomes more uniform in thickness and density; the rate of yield of 90 concentrates at different portions of the machine is more nearly the same; and the output efficiency of the machine is increased for these 95 reasons.

It follows from what has just been said that the inverted bowl type of separator may 100 be operated at lower rotative speeds than the upright bowl types. This reduction of speed coupled with the fact that it is not necessary to raise the material therein against gravity, calls for less expenditure of power 105 and, in combination with the lower center of gravity of the inverted bowl, results in much less vibration and more satisfactory 110 mechanical operation.

Another advantage of the inverted bowl, 115 and its more nearly cylindrical shape, is the very slight difference in diameter between the top and bottom of retaining bands 22. In the upright bowl the equivalent skirt ring construction necessarily has to have a much 120 greater difference in the corresponding diameters, since the concentrates are retained therein by centrifugal force opposing gravity. It follows that the spouting velocity of the jets required to remove the concentrates 125 on the inverted bowl of the present invention need be only a fraction of what is required in the case of the former upright bowl types with their skirt rings. Ordinarily only mill or city water pressure is required for the 130

inverted bowl. A further saving in power is made in this way since the retarding effect of the jets on the bowl is much less.

I desire to call attention to the fact that, 5 although the drawings illustrate a complete operative structure embodying the principles of my invention, I have simplified the construction as much as possible to avoid unnecessary confusion. There are a number of 10 structural features, as for instance the nozzle assembly and details, that perhaps could be elaborated to practical advantage; and the proportions and relation of parts can be varied, in many respects, as desired. For instance it may be desirable to make use of 15 compressed air jets instead of water jets, or to do away with jets altogether and make use of scrapers or other purely mechanical devices in their place. The number of ducts 20 at 28 may be changed, the number of the segregating launder banks may be raised or lowered, and different means may be employed for distributing the pulp upon the upper peripheral wall of the revolving bowl. Such 25 changes are contemplated by me in the construction of commercial machines.

Having thus fully described my invention in a manner that will make its construction and operation clear to those familiar with the 30 art involved, I claim:—

1. A centrifugal separator comprising; an inverted rotatable bowl having circumferentially arranged orifices in its peripheral wall; means for feeding material into the revolving bowl against its peripheral surface above said orifices; means for rotating the bowl at a speed adapted to cause the material to cling to said surface while working downwardly; means on the outside of the bowl for retaining material discharged from the orifices to 35 variably obstruct the flow therethrough; and means for continuously removing said discharged material.

2. A centrifugal separator comprising; an inverted rotatable bowl having plural circumferential rings of arcuate orifices in its peripheral wall; means for feeding material into the revolving bowl against its peripheral surface above said orifices; means for rotating 40 the bowl at a speed adapted to cause the material to cling to said surface while working downwardly; annular channels on the outside of the bowl having outer walls opposite the orifices and adapted to catch and retain material discharged therefrom to variably obstruct the flow therethrough; and means for continuously removing said discharged material.

3. A centrifugal separator comprising; an inverted rotatable bowl having plural circumferential rings of arcuate orifices in its peripheral wall and circular flanges on its outer surface; means for feeding material into the revolving bowl against its peripheral surface above the orifices; means for rotating 50

the bowl at a speed adapted to cause the material to cling to said surface while working downwardly; circular bands extending upwardly from said flanges above the orifices to form channels adapted for catching and retaining material discharged therefrom to variably obstruct the flow therethrough; and means for continuously removing said discharged material at controllable rates. 70

4. A centrifugal separator comprising; an inverted rotatable bowl having plural circumferential rings of arcuate orifices in its peripheral wall and an axial quill-shaft; means whereby material may be fed into the revolving bowl through said shaft and against the peripheral surface of the bowl above the orifices; means for rotating the bowl at a speed adapted to cause the material to cling to said surface while working downwardly under the influence of gravity; annular channels on the outside of the bowl having outer walls opposite and extending above the orifices whereby material discharged therefrom may be caught and retained to variably obstruct the flow therethrough; and means for directing a plurality of angularly spaced jets downwardly into each of said channels whereby said discharged material may be washed upwardly to be centrifugally thrown from the bowl. 85 90

5. A centrifugal separator comprising; an inverted rotatable bowl having plural circumferential rings of arcuate orifices in its peripheral wall; means whereby material may be fed into the revolving bowl against its peripheral surface above the orifices; means for rotating the bowl at a speed adapted to cause the material to cling to said surface while working downwardly; means for retaining circumferential banks of material on the outside of the bowl opposite the orifices to variably obstruct the flow therethrough; and means for directing a plurality of angularly spaced jets against each of said banks whereby material may be removed therefrom at controllable rates; said jets being so positioned that each is adapted to cooperate with the preceding jet of its series to prevent material dislodged thereby from being returned to its bank. 100 105 110

6. A centrifugal separator comprising; an inverted rotatable bowl having circumferentially arranged arcuate orifices in its peripheral wall and a tubular journal at the top through which material may be introduced; a plate fixed within the bowl below said journal and above the orifices whereby said material may be centrifugally thrown against the inner surface of said wall; means for rotating the bowl at a speed adapted to cause the material to cling to said surface while working downwardly; means for retaining circumferential banks of material, on the outside of the bowl opposite the orifices to variably obstruct the flow therethrough; means for directing a plurality of angularly spaced 115 120 125 130 135

- jets against each of said banks whereby material may be removed therefrom at controllable rates to be centrifugally thrown from the bowl; and means for separately collecting the material thus removed from the respective banks; said jets being so positioned that each is adapted to cooperate with the preceding jet of its series to prevent material dislodged thereby from being returned to its bank.
10. 7. A centrifugal separator comprising; a rotatable bowl having means for segregating exterior circumferential banks of material upon its peripheral wall; means for removing material from said bank separately; and a housing surrounding the bowl having interior circumferential pockets respectively adapted for receiving material removed from the banks; and exterior circumferential launders respectively communicating with the interior pockets.
8. A centrifugal separator comprising; a rotatable bowl having means for segregating exterior circumferential banks of material upon its peripheral wall; means for removing material from said banks separately to be centrifugally thrown from the bowl; a housing surrounding the bowl having interior circumferential pockets respectively adapted for catching material thrown off from the banks, and exterior circumferential launders respectively communicating with the interior pockets; and selective means for discharging the launders separately or in desired combinations.
35. 9. A centrifugal separator comprising; a rotatable bowl having means for segregating exterior circumferential banks of material upon its peripheral wall; angularly spaced means for removing material from each of said banks; and a housing surrounding the bowl having interior circumferential pockets respectively adapted for receiving material removed from the banks, and exterior circumferential launders respectively communicating with the interior pockets; each of said
- pockets and launders being sub-divided by partitions whereby the products of the said removing means may be separated.
10. A centrifugal separator comprising; a rotatable bowl having means for segregating exterior circumferential banks of material upon its peripheral wall; angularly spaced means for removing material from each of said banks separately to be centrifugally thrown from the bowl; a housing surrounding the bowl having interior circumferential pockets respectively adapted for catching material thrown off from the banks, and exterior circumferential launders respectively communicating with the interior pockets; partitions subdividing each of said pockets and launders whereby the products of the said removing means may be separated; and selective means for discharging the subdivisions of the launders separately or in desired combinations. 50
11. A construction as set forth in claim 7 wherein the launders and interior pockets are oppositely disposed on the shell of the housing and are in communication through relatively long circumferential orifices in the shell. 55
12. A construction as set forth in claim 7 wherein the launders and interior pockets are oppositely and helically disposed on the shell of the housing and are in communication through relatively long circumferential orifices in the shell at the bottoms of the launders and pockets. 60
13. A construction as set forth in claim 8 wherein the selective discharging means consist of upright ducts with pluggable orifices therein respectively communicating with the launders. 65
14. A construction as set forth in claim 10 wherein the selective discharging means consist of upright ducts with pluggable orifices therein respectively communicating with the subdivisions of the launders. 70
